United States Patent Office

Des. 203,852
Patented Feb. 22, 1966

203,852

BEVERAGE SERVER

David Douglas, Manitowoc, Wis., assignor to East Wisconsin Trustee Company of Manitowoc, Manitowoc, Wis., a corporation of Wisconsin

Filed June 23, 1965, Ser. No. 85,871

Term of patent 14 years

(Cl. D44—21)

FIG. 1

FIG. 2

FIG. 5

FIG. 1 is a side elevational view of a beverage server showing my new design;

FIG. 2 is a top plan view;

FIG. 3 is a front elevational view;

FIG. 4 is a rear elevational view;

FIG. 5 is a side elevational view of the cover member, removed from the server;

FIG. 6 is a sectional view taken along line 6-6 of FIG. 1; and

FIG. 7 is a sectional view taken along line 7-7 of FIG. 4.

I claim:

The ornamental design for a beverage server, substantially as shown.
